UNITED STATES PATENT OFFICE

LUDWIG EIRICH AND JOSEPH EIRICH, OF HARDHEIM, BADEN, GERMANY

DISCHARGING CLOSURE FOR MIXING MACHINES

Original application filed July 8, 1926, Serial No. 121,181, and in Germany November 13, 1924. Divided and this application filed February 8, 1928. Serial No. 252,867.

This invention relates to a discharging closure on mixers, stirring machines, mortar mills, slowly rotating cylinders and the like for masses of any kind, especially for ceramic masses, in which in the bottom of the mixing drum an aperture is arranged for which a closing piece moved like a slide and adapted to be raised and lowered is mounted. Stirring devices which move directly over the plate-like bottom push the material towards the aperture in the bottom through which it drops into a truck placed underneath.

The closing cover together with a mechanism for adjusting in vertical directions might further be arranged in a casing suspended on a pivot pin underneath the mixing drum so that it can be oscillated in horizontal direction. The oscillatable arm has means and arrangements which permit of rapidly moving the closing cover upward- and downward by one single manipulation and to bring the whole by a lateral pressure out of the area of the discharging aperture.

A form of construction of the machine is shown, by way of example, in the accompanying drawing, in which:

Fig. 1 is a vertical longitudinal section through the device with oscillatable arm.

Fig. 2 shows in plan view seen from below the device shown in Fig. 1.

The mechanism comprising an oscillatable arm, as shown in Figs. 1 and 2 is constructed as follows:—The rotatable mixing drum *a* has at the center of its bottom plate *b* a discharging aperture *d*¹. In Fig. 1 the closing cover *d* is shown in the extreme lower position, from which it can be oscillated in lateral direction.

The closing cover *d* is mounted, by means of a stud *e*, in a bearing sleeve *f* which is arranged in a casing *g*. The casing *g* is oscillatably mounted on an axle *h* which is connected by a connecting element *i* to a U-iron *k* fixed underneath the mixing machine. The lowering and raising of the closing cover *d* is effected through the intermediary of an elbow lever pivotally mounted in the casing *g*, the ball-shaped end of the upper arm *l* of said elbow lever engaging with a cavity of the bearing *f*, a connecting rod *n* being hingedly

connected to the end of the other arm *m* of said elbow lever. This connecting rod *n* is mounted in a tube *o* which is fixed in a casing in which the elbow-lever is enclosed. The other end of the connecting rod *n* merges into a screw spindle *p* which is screwed into an internally threaded sleeve *r*. This sleeve *r* is rotatably mounted on the flange *o*, of tube *o* and it has a crank handle *s*. From this screw spindle *p* extends a rod *p*₁ on the end of which two nuts *t* are screwed which serves as a stop for the crank handle, the other stop for said handle being formed by the end of the screw spindle *p*. If the crank handle *s* is turned in the one or other direction the rod *n* is either shifted to the left or right. The arm *l* of the elbow lever is thus made to raise or lower the sleeve *f* with the closing cover *d* which is thus rapidly and in a simple manner brought into the desired position. If the closing cover *d* is in the extreme position the mechanism and the closing cover can be rotated around the stud *h* to liberate the aperture *d* so that the material can drop out of the same.

We claim:—

1. A discharging closure for mixing machines, stirring machines, mortar mills or the like for masses of any kind, consisting of a closing cover underneath the discharging aperture in the bottom plate of the machine, a laterally oscillatable structure on which said closing cover is mounted, a pivot pin on which said structure is mounted, and a crank handle on one end of said structure by which to operate said cover.

2. A discharging closure for mixing machines, stirring machines, mortar mills or the like for masses of any kind, consisting of a closing cover underneath the discharging aperture in the bottom plate of the machine, a guide stud fixed on the lower surface of said closing cover, a sleeve in which said guide stud is located, an oscillatable casing in which said sleeve is mounted, and means for raising and lowering said closing cover, said means consisting of an elbow lever pivotally mounted in said casing one arm of said elbow lever engaging with said sleeve, a connecting rod hingedly connected to the other

arm of said elbow lever, a screw spindle forming part of said connecting rod, an internally threaded sleeve on said screw spindle, and a crank handle for rotating said 5 sleeve.

3. A discharge closure for bottom discharge mixing machines, consisting of a closing cover underneath the discharge aperture in the bottom of the machine, a vertically oscillatable stud on which said cover is mounted, a sleeve in which said stud is mounted to rotate, laterally oscillatable means in which said sleeve is mounted for vertical movement, a connecting rod, means operated by reciprocation of said rod to raise and lower said sleeve, and a manually operated device mounted on the laterally oscillatable means to reciprocate said rod to raise and lower said sleeve to open and close the cover while permitting its rotation.

In testimony that we claim the foregoing as our invention, we have signed our names hereto.

LUDWIG EIRICH.
JOSEPH EIRICH.
